Patented Oct. 6, 1970

218,909

COMBINED HANDLE AND SPOUT FOR A TEA KETTLE OR THE LIKE

Mikio Nakamura, Toronto, Ontario, and Lawrie G. Mc-
Intosh, Islington, Ontario, Canada, assignors to
McGraw-Edison of Canada Limited, Toronto, Ontario,
Canada, a corporation of Canada

Filed Mar. 7, 1969, Ser. No. 16,124

Term of patent 14 years

Int. Cl. D7—99

U.S. Cl. D44—26

FIG. 1

FIG. 2

FIG. 3

FIG. 4

FIG. 1 is a perspective view of a combined handle and spout for a tea kettle or the like;

FIG. 2 is a side elevational view thereof;

FIG. 3 is a front elevational view thereof; and

FIG. 4 is a rear elevational view thereof.

We claim:

The ornamental design for a combined handle and spout for a tea kettle or the like, substantially as shown.
